8 Claims. (Cl. 179—6)

The invention relates to an arrangement for telephone systems suitable for automatic connection of calling subscribers A with a central message office in case the called subscriber B is not available to answer the call, permitting the interchange of messages in both directions by means of simple auxiliary devices disposed at the subscribers B and of a combined switching and indicating device, common for a group of such subscribers B.

Arrangements for similar purposes are in use, but these known arrangements do not allow the subscribers B to send messages to the calling subscribers A without a previous call of B to the message office. In these known arrangements the recording of these messages in the message office requires a great amount of operator's work, furthermore they have the drawback of comparatively high first cost for each subscriber and in some cases of considerable power consumption even during the time of no conversation.

On the other hand, the arrangement according to the present invention is such that frequently wanted, stereotype messages of the subscriber B which he desires to be transmitted to all subscribers A calling him, are neither to be communicated beforehand to the message office, nor to be recorded there and to be selected from these records in case of a call of a subscriber A. The stereotype message set up by B is automatically indicated to the operator of the message office simultaneously with the call of subscriber A or the message is transmitted by means of suitable reproducing apparatus in a fully automatic manner.

In the figures of the annexed drawings

Fig. 1 shows diagrammatically, the arrangement in principle of an apparatus according to the invention,

Figs. 2 and 3 each illustrate an embodiment, shown by way of example, of an apparatus according to the invention,

Fig. 4 shows the detail of a further arrangement, in principle, and

Figs. 5 and 6 illustrate details appertaining to the embodiment shown in Fig. 2 and in Figs. 2 and 3, respectively.

The idea of the invention is best explained by reference to the diagram shown on Fig. 1. An auxiliary device 1 is provided at subscribers B, this device being operated by B, if he desires that subscribers A, calling him thereafter, shall be connected to the message office. There is also a central combined switching and indicating device 2, common for a group of subscribers B. By operating the auxiliary device 1, peculiar predetermined current and voltage conditions may

be produced in line 3 of subscriber B, and thereby, according to the invention, device 2 is influenced in such a manner that a calling subscriber A is connected automatically to the message office and the interchange of messages is made possible either over the operator's set N or by means of automatic speech or signal recording and reproducing apparatus Z. According to the invention, for each message chosen by B from a plurality of stereotype messages to be transmitted to calling subscribers A, there is a corresponding predetermined different manner of operation of device 1, causing corresponding peculiar current and voltage conditions in line 3 and a corresponding manner of influencing device 2. The manner in which device 2 has been influenced is observed by the operator at N who transmits the corresponding stereotype message to the subscriber A or this message is communicated automatically, according to the manner in which device 2 has been influenced, by means of apparatus Z in form of signals or speech reproduction. Transmission of messages which are not stereotype addressed by B to A and recorded beforehand, and the recording of messages addressed by A to B, are effected either by operators or by automatic recording and reproducing apparatus Z. As shown hereinafter, for communications between B and the message office a direct connection over device 2 and line 3 may be used without any cooperation of the normal switching apparatus of the exchange.

An embodiment of the invention is shown in Fig. 2. A is the calling subscriber, B the called subscriber, VA the automatic telephone exchange, to which B is connected, 1 the auxiliary device at B, 2 the common switching and indicating device for all subscribers of the same exchange VA, and a and b the two wires of line 3 of subscriber B. The auxiliary device 1 comprises in this case the switch S and a variable alternating current resistance, composed of a variable condenser K and a variable induction coil W; for each stereotype message of B a fixed value of the A. C. resistance is allotted with fixed values of K and W. The wires a and b of subscribers B are connected to corresponding contacts of two contact banks of finder Sr, having three wipers. The primary windings of transformers T are arranged in wires b, whilst one end of the secondary windings is grounded and the other end is wired to the third contact bank of finder Sr. The finder is permanently driven by the stepping magnet M₁, as long as there is no incoming call for a non-answering subscriber B. When a call is

made to a subscriber B who has operated his switch S, thereby disconnecting his subscriber's set and connecting up his auxiliary device 1, a ringing current of less intensity will result, the resistance of device 1 at the frequency of the ringing current being greater than that of the subscriber's set. As soon as the finder Sr reaches the contacts of B, the ringing voltage is transmitted by wipers Sa and Sb to the amplifier V1 and in its output circuit relay R1 will operate. At the same time amplifier V2 is also influenced by transformer T and wiper St, but relay R2 in the output circuit of amplifier V2 does not operate, this latter being adjusted to operate only if the normal ringing current is flowing in wire b. In this way relay R3 is energized by r1 and r2, operates and opens at r_{m1} the circuit of magnet M₁, and in consequence thereof finder Sr stops. R₃ locks up through r_h and wires a and b are extended by r₁ and r₂, after having been momentarily short-circuited during switching at the pre-contacts r_{av} and r_{bv}, so as to bring the apparatus in the exchange VA into the talking position. Finally the circuit of stepping magnet M₂ of selector Wa is closed at r_{m1}. Selector Wa rotates and by its wiper Wt successively connects different oscillating circuit Sk to the grid of oscillator tube Se; each frequency of the oscillator tube corresponds to a frequency tuned up by a certain setting of device 1. As soon as the same frequency is sent which corresponds to the setting of device 1, there results a resonance current in line 3 which operates relay R4 by transformer T₁ and amplifier V3. This relay opens the circuit of magnet M₂ at r_{m4}, selector Wa stops and R₄ locks up through r_{m4}. The operator's set N and at the same time one of the talking machines Z are connected up at r₄ and by wiper Wz respectively. Each of the talking machines transmits one of the stereotype messages and these talking machines are connected to the contacts of the arc of movement of the wiper Wz in the proper sequence, so that the caller has transmitted to him the message which corresponds to the manner in which the auxiliary device has been operated. The talking machine thus transmits to subscriber A any stereotype message set on device 1, the operator communicates the special non-stereotype message of B and records the message of A addressed to B. There the operator presses the key Tr, thereby releasing device 2 and the operation may thereupon be repeated as described.

Another embodiment is shown in Fig. 3. The auxiliary device 1 consists in this case of an alternating current drop F, connected across wires a and b in series with a condenser K, and of a buzzer Su in series with a stepping magnet M connected also across the wires a and b as soon as the drop F falls. The stereotype message is set up by adjusting stop An, engaging e. g. with a cam disc, thereby allowing a ratchet wheel K₁ driven by magnet M and keyed on a common shaft with the cam disc, to rotate a certain number of steps corresponding to the serial number of the message. Device 2 comprises a finder Sr with two wipers. The wires a and b of subscribers B are connected to the contact banks of Sr. Wipers Sa and Sb are connected by back contacts of R₁ to the input terminals of a band-pass amplifier V tuned to the frequency of buzzer Su. The winding of relay R₁ is connected to the output terminals of amplifier V. When switch S has been closed and B is called, drop F falls under action of the ringing current; magnet M and buzzer Su are energized; but the armature of M

cannot follow the quick vibrations of the buzzer, in consequence whereof it remains attracted during the time the buzzer is working. As soon as the finder Sr reaches the line of B, relay R₁ is energized by V, operates and opens at r_m the circuit of the stepping magnet M₁ of finder Sr, and as a result Sr stops. R₁ locks up through r_h and r₄ and extends the wires a and b along r₁ and r₂. This done, relay R₂ operates by r₁ and the loop of subscriber B, the wire a being earthed in VA. R₂ closes at r₂ the circuit of stepping magnet M₂ of an indicator dial Sch, M₂ operates, Sch makes a step and M₂ grounds wire b by contact E, in consequence whereof magnet M of device 1 is released and the ratchet wheel K₁ makes a step 15 accordingly. Magnet M₂ comprises a self-interrupter, not shown in the figure, which opens the energizing circuit as soon as the armature has been attracted, therefore M₂ falls back after each attraction. This play of M₂ and M is repeated 20 until the rotation of ratchet wheel K₁ is limited by the stop An. Then the ratchet wheel K₁ returns to its normal position under action of a spring, not shown on the figure, tensioned during the stepping of K₁ and released by An; drop F is 25 at the same time restored mechanically. Thus the loop of subscriber B, i. e. the circuit of R₂, is opened, and in consequence M₂ cannot be energized again. Dial Sch stops after as many steps as the ratchet wheel K₁ was allowed to perform 30 by the adjustable stop An. Contact K₂ which is open only in the normal position of dial Sch, is now closed and relay R₃ is energized by the back contact r₂, disconnecting R₂ from wire b at r₂ and extending wires a and b along r_{1a} and r_{2a} to the 35 operator's set N. Now the operator can read the stereotype message indicated by the position of dial Sch and recognizes from the position of finder Sr, which subscriber has been called. After the communication and reception of the messages 40 the operator presses key Tr, thereby mechanically releasing dial Sch which returns to normal position under action of a spring. Relay R₄ is energized by the front contact of key Tr and locks up through contacts r_{1h} and r_{2h}. As soon as dial Sch has reached its normal position, the circuit of relay R₄ is opened at contact K₂, then R₃ releases, the operator's set is disconnected, and the locking circuit of R₄ is opened at r_{2h} and that of R₁ is opened at r_{1h}. The circuit of M₁ is closed again at r_m. Finder Sr moves on and the whole operation is repeated as soon as it reaches the line of another subscriber who may be called and who does not answer.

In the case of both arrangements presented the 45 employment of individual relays for each subscriber for the device 2 has been avoided, this being rendered possible by the employment of the amplifiers described, by means of which the signals arriving from the various lines are transmitted to the common relays. Arrangements are, however, also possible, which do not require any amplifier but require the employment of individual relays for each subscriber.

The action of the auxiliary device 1 by which it connects A with device 2 and the signal transmission between devices 1 and 2 i. e. the kind of peculiar current and voltage conditions caused by device 1 in line 3, may be different from those of the embodiments described above. For example, device 2 may be influenced by varying the intensity, frequency, phase, continuity or some other characteristics of the ringing or feed current, or by supplying currents or voltages from foreign sources provided at B or elsewhere which 75

are influenced by device 1 and affect device 2 over line 3 accordingly.

According to the invention the operation of the switching and indicating device 2 may be made automatic in a greater measure than described as above e. g. by using for recording of the messages of A addressed to B speech recording apparatus acting in a well known manner.

In the message office provision is to be made for one or, depending on traffic requirements, more office lines for communication with subscribers. According to the invention a direct connection over lines 3 and device 2 may be used for the communication between subscribers B and the message office, without the cooperation of the switching apparatus of exchange VA whereby a certain manner of operation of auxiliary device 1 may set up a direct connection with the operator's set N over line 3 and device 2. For example, in the embodiment of Fig. 3 this may be effected by directing the buzzer's tone from the auxiliary device 1 over the resistance W₁ and switch S₁ in Fig. 5 to the line 3, thereby causing device 2 to stop on the respective line 3 and to establish the connection to N in the manner described above.

According to the invention an additional device may be provided at B which indicates if B has been called during the non-answering period, in order to induce B to inquire at the message office. Furthermore the calls may be registered at B or in the message office by means of metering devices e. g. for accounting purposes, or the time of engagement of device 2, of the operator, or of apparatus Z may be recorded continuously and separately for each subscriber.

During the time when device 1 is in the non-answering condition, the bell may be left connected, possibly with a weaker tone, in order to make B cognizant of the call, should he have forgotten to restore his device 1 into the answering condition. By these means the operator is enabled to give a special ringing signal to subscriber B in urgent cases and in those which have been previously pointed out by B or marked as desirable by setting his device 1 accordingly.

According to the invention if the traffic with the message office is very intensive, further switching and indicating devices 2' shown in Fig. 1 may be employed for the same group of subscribers, in which case provision should be made in ways for avoiding double connections.

On the other hand, certain parts of the switching and indicating device may also be common for various groups of subscribers, as shown in Fig. 4. In other cases, when the traffic is moderate, as at night, etc. the service of several devices 2 serving different groups of subscribers (e. g. in different exchanges VA) may be combined; in this case some parts of device 2 will be situated at a considerable distance from the others and connected with them over trunk lines. In such cases such indications of device 2 which cannot be read directly, are to be transmitted to the operator over trunk lines in known manner.

In order to accelerate operation, according to the invention, lamp indicators working in well known manner may be used for the indication of the positions.

A certain part of the stereotype messages will be the same for all subscribers B, e. g. the cause of failure to answer: absence, nighttime etc.; furthermore certain limitations of answering, e. g. only for toll calls; finally the time of the next reply condition and the like. According to the

invention, provision can be made for a number of stereotype messages different for each subscriber B, e. g. communication of the directory numbers, at which he may be reached at the time being. In this case the selection of the meaning of various readings of device 2 for each subscriber B from records by the operator may be avoided by the use of a combined indicating apparatus for this kind of messages—stereotype for anyone subscriber B, but different for different subscribers B—the indications thereof being dependent not only on the particular subscriber B who was called, but also on the setting of the called subscriber's device 1. Such a combined indicating apparatus is shown in Fig. 6. Wiper S₁ is fixed on the shaft of the finder S₇ whilst wiper S₂ is fixed on the shaft of the disc S₆ as in Fig. 3, so that wiper S₁ will switch the indicator lamp of the called subscriber, whilst wiper S₂ will switch the indicator lamp corresponding to the serial number of the message. Thus the message to be transmitted may be read at the crossing point of the row and column marked by lit up lamps.

Having now fully described and ascertained our said invention and the manner in which it is to be performed, we declare that what we claim is:

1. A telephone system for the interchange of messages between calling and non-answering called subscribers, comprising a message office, an auxiliary device at the called station operable to produce predetermined different current or voltage conditions in the called line, means for setting said auxiliary device to operate in a selected manner, a signal operable in predetermined different ways corresponding to the different settings of said auxiliary device, switching and indicating apparatus common for a group of called subscribers and responsive to said different current or voltage conditions, and means controlled by said apparatus for connecting the calling subscriber to the message office and for actuating said signal in accordance with the setting of said auxiliary device.

2. A telephone system for the interchange of messages between calling and non-answering called subscribers, comprising a message office, an auxiliary device at the called station operable to produce predetermined different current or voltage conditions in the called line, means for setting said auxiliary device to operate in a selected manner, a signal operable in predetermined different ways corresponding to the different settings of said auxiliary device, switching and indicating apparatus common for a group of called subscribers and including finders responsive to the different current or voltage conditions in a particular called subscriber's line, and means controlled by said apparatus for connecting the calling subscriber to the message office and for actuating said signal in accordance with the setting of said auxiliary device.

3. A telephone system as set forth in claim 2, said finders comprising parts adapted to move in a step-by-step manner.

4. A telephone system for the interchange of messages between calling and non-answering called subscribers, comprising a message office, an auxiliary device at the called station operable to produce predetermined different current or voltage conditions in the called line, means for setting said auxiliary device to operate in a selected manner, a signal operable in predetermined different ways corresponding to the different settings of said auxiliary device, switching and indicating apparatus common for a group of called

5 subscribers and responsive to said different current or voltage conditions, and means controlled by said apparatus for connecting the calling subscriber to the message office and for actuating said signal in accordance with the setting of said auxiliary device; said switching apparatus comprising an amplifier responsive to said different current or voltage conditions, and finders influenced by said amplifier, said finders comprising parts adapted to move in a step-by-step manner.

10 5. A telephone system for the interchange of messages between calling and non-answering called subscribers, comprising a message office, an auxiliary device at the called station operable to produce predetermined different current or voltage conditions in the called line, means for setting said auxiliary device to operate in a selected manner, a signal operable in predetermined different ways corresponding to the different settings of said auxiliary device, switching and indicating apparatus common for a group of called subscribers and responsive to said different current or voltage conditions, and means controlled 20 by said apparatus for connecting the calling subscriber to the message office and for actuating said signal in accordance with the setting of said auxiliary device; said switching apparatus comprising a means responsive to said different current or voltage conditions, and finders influenced by said means, said finders comprising parts adapted to move in a step-by-step manner.

25 6. In a telephone system, the combination with the elements set forth in claim 1 of an indicating device associated with said switching apparatus, and means for automatically causing said indicating device to function so as to indicate which particular subscriber has been called.

7. In a telephone system, an unattended subscriber's station, a subscriber's set, a message-storing and -sending device having a plurality of possible settings corresponding to different predetermined stereotype messages and connectable to said subscriber's line, an operator's position, an operator's set, an indicating device at said operator's position, a switch having access to said subscriber's line and responsive to a call incoming to said subscriber's line for completing a talking connection between the calling subscriber and the operator at said position and simultaneously establishing a signal transmission over said subscriber's line between said message-storing and -sending device and said indicating device.

10 8. In a telephone system, an unattended subscriber's station, a subscriber's set, a message-storing and -sending device having a plurality of possible settings corresponding to different predetermined stereotype messages and connectable to said subscriber's line, an operator's position, an operator's set, an indicating device at said position, a switch having access to said subscriber's line and responsive to a call incoming to 20 said line for completing a talking connection between the calling subscriber and the operator at said position and simultaneously establishing a signal transmission over said subscriber's line between said message-storing and -sending device and said indicating device, said message-storing and -sending device and said message-indicating device both comprising parts movable in a step-by-step manner and adapted to operate in synchronism if connected one to the other over said 25 subscriber's line.

ADALBERT SZILARD.
GEORG KELETI.
